W. L. ECKHARDT

SOUND CONVEYING MEANS FOR TALKING MACHINES

Filed Dec. 8, 1920

UNITED STATES PATENT OFFICE.

WALTER L. ECKHARDT, OF PHILADELPHIA, PENNSYLVANIA.

SOUND-CONVEYING MEANS FOR TALKING MACHINES.

Application filed December 8, 1920. Serial No. 429,066.

To all whom it may concern:

Be it known that I, WALTER L. ECKHARDT, a citizen of the United States, and a resident of Philadelphia, in the county of Philadelphia and State of Pennsylvania, have invented an Improvement in Sound-Conveying Means for Talking Machines, of which the following is a specification.

My invention relates to sound conveying means for talking machines, and it has for one of its objects to provide means whereby the reproduced talking and musical tones are richer and more pleasing to the ear of the listener than such tones heretofore have been; that is, by the employment of my invention the quality of the reproduced sounds, both vocal and instrumental, is improved.

It is also an object of my invention to provide means adapted to be associated and combined with the ordinary sound conveying or tone-arm of a talking machine to effect an improvement in the tone and quality of the sounds, vocal and instrumental, which may be reproduced thereby.

A further object of my invention is to provide means whereby a body or reservoir of fluid, such as air, may be contained in surrounding or enveloping relation with respect to the sides of a sound conveying or tone-arm of a talking machine. It is believed by me that one reason why the presence of an air-tight or practically air-tight chamber filled with a fluid, such as air, surrounding the sides of a sound conveying or tone arm of a talking machine causes an improvement in the quality of reproduced sounds is that such presence more effectively confines the sound wave vibrations within the said arm; that is, prevents or diminishes

dissipation thereof, whereby more nearly the full effect of the sound waves produced by and emanating from the diaphragm of the sound box is transmitted to the amplifier proper of the machine. It is also believed that the presence of such air tight air or gas filled chamber surrounding the sides of the arm shields the sound producing vibrations within the sound conveying or tone arm against extraneous disturbing influences and thereby permits and causes delivery thereof from the said arm to the amplifier of the machine in a more natural condition; that is, the form and condition thereof, except as

amplified, as originally produced and initiated by the diaphragm of the sound box. 55 Although it is believed that the foregoing reasons adequately explain why the employment of my invention improves the reproduced sounds of a talking machine, I desire to have it understood that the invention is 60 not dependent upon the correctness or incorrectness of the foregoing or any other explanation which may be advanced. The essential thing is that the employment of the novel means embodying my invention 65 accomplishes an important new result.

A further object of my invention is to provide an improvement in the means for connecting the sound conveying arm or tone arm to the top of the cabinet or casing of 70 the machine or to a stationary member or element secured to such top.

Other objects and advantages of my invention will be pointed out in the detailed description thereof which follows or will 75 be apparent from such description.

In order that my invention may be easily understood and its practical advantages fully appreciated, reference should be had to the accompanying drawing in which one form 80 of embodiment of my invention is shown. It will be understood however that changes in the details of construction may be made within the scope of the claims without departing from the said invention. 85

In the drawing:

Fig. 1 is a view in central vertical section of portions of the upper part of a talking machine provided with a sound conveying arm or tone arm provided with my invention; 90

Fig. 2 is a top plan view thereof; and

Fig. 3 is a view in vertical section of portions of the said arm showing in detail how it is pivotally secured to a tubular bracket 95 which is in turn stationarily secured to the top of the cabinet or casing of the machine.

Referring to the drawings: 1 designates the sides of a cabinet which may be of any known construction and 2 the top thereof, to the under side of which the motor 3 is secured. The turn table 5 for supporting the records, one of which is shown at 6, is secured to the upper end of the motor shaft 7 and rotates therewith in the usual manner. 100

The stylus 10 for engaging the record 6

has operative connection with the sound box 11 which latter may be of any known construction. The sound box is provided with a rearwardly extending tubular projection 12, the rear end of which terminates in a spherical portion as shown at 13 which is in pivotal engagement with the interior of a like spherical portion 14 at the forward end of the tubular sound conveying arm or tone-arm comprising the parts or sections 15 and 17. The spherical portions 13 and 14 are provided with additional connections consisting of horizontally arranged pivots 16 about which the sound box may be moved 18 pivotally.

The rear portion of the part 15 of the tone-arm extends substantially at right angles to the remaining front portion thereof and is provided at its rear end with an internally screw threaded expanded portion 16^a with which is engaged the upper end of the part 17, the lower end of which is flared or belled, as shown. The lower flared end of the part 17 terminates within the upper end portion of an amplifier or horn 18 a short distance below the upper end thereof. The said horn may be of any known construction.

By extending the rear end of the tone-arm into the upper end portion of the amplifier or horn 18 as shown, all of the sound vibrations transmitted through the said arm are delivered to the horn without loss, to be transmitted thereby. If the rear end of the tone-arm terminated in a plane in front of or co-incident with the adjacent small end of the amplifier or horn 18 an opportunity for leakage of the sound vibrations would be afforded. The dissipation of the sound vibrations at this point is avoided by my construction in which the rear end of the tone-arm extends into the upper end portion of the amplifier or horn 18.

The air tight closed chamber previously referred to which surrounds the sides of the tone arm 15 is formed by means of an inclosing casing 20 which, in the construction shown, is of tapering formation but may be of any other shape. The essential thing is that it shall inclose the sides to form a chamber surrounding the said tone-arm. At its forward end the casing is connected to the tone-arm. This connection may be effected by brazing, soldering or in any other way which may be desired and found to be practical. As in the case of the tone-arm the rear end portion of the casing extends substantially at right angles to the remaining front portion thereof. The rear ends of the part 15 of the tone-arm and casing 20 terminate in practically the same plane and are connected or secured together by means of an annular plug 21 which is situated in the space between the rear end of the said casing 20 and the ex-

panded portion 16 of the part 15. The plug 21 is secured to the rear ends of the part 15 and the casing 20 and seals the chamber surrounding the said part 15 formed by the casing 20. The bottom side of said plug is flush with the adjacent edge of the parts 15 and 20.

The edges of the rear ends of the part 15 of the tone-arm and casing 20 and the outer rear side of the plug 21 (which also may be regarded as a bearing means) rest upon the upper side of an inwardly extending flange 22 upon a tubular bracket 23 secured to the upper side of the top 2 of the cabinet. The rear ends of the part 15 of the tone-arm and casing are retained in position upon the flange 22 by means of a flange-like collar 24 secured to the part 17 of the tone-arm near the end thereof which is secured to the rear end of the part 15. There should be slight play between the collar 24 and the flange 22,—just sufficient to permit free pivotal or rotary movement of the tone-arm and casing about a vertical axis upon the said flange so as to permit lateral swinging movements of the tone-arm, casing, sound box and stylus over the record 6.

It will be seen that in addition to providing means whereby the quality of the reproduced sounds, vocal or instrumental, is improved, I have also provided means whereby the tone-arm may be readily and easily connected with and disconnected from the tubular bracket 23. The assembling of these parts and the connection thereof to the top 2 of the cabinet are thereby greatly facilitated.

Having thus described my invention, what I claim and desire to secure by Letters Patent, is:

1. In combination, a tubular tone-arm for a talking machine comprising front and rear parts, the front part being of uniform diameter and having an expanded portion at its rear end, and the said rear part having detachable connection with said expanded portion, a bearing means provided upon the outer side of said expanded portion, the lower side of which is flush with the adjacent edge of the said expanded portion, an annular support for the said bearing means, and means provided upon the said rear part of the tone-arm and being situated practically in contact with the lower side of the said annular support and co-operating with the said bearing for connecting the tone arm to the said annular support.

2. In combination, a tubular tone arm, a casing inclosing the sides of the tone arm from a point adjacent its front end to a point near its rear end and being spaced therefrom to form a chamber surrounding the same, an annular member situated in the annular space between the rear end of the

said casing and the adjacent portion of the said arm, the said annular member being secured to the said casing and to the adjacent portion of the said arm, a bracket having an inwardly extending flange upon which the said annular member is supported, and a collar secured to the rear part of the said tone arm which collar occupies a position adjacent the flange of said bracket in opposed relation to the rear end of the said 10 casing and to the said annular member.

In testimony that I claim the foregoing as my invention I have hereunto set my name this 29th day of November, A. D. 1920.

WALTER L. ECKHARDT.
